Application November 25, 1936, Serial No. 112,687
In Italy November 30, 1935

6 Claims. (CL 265—2)

This invention relates to machines for the mechanical test of yarn strength.

An object of this invention is to insure a more reliable working than could be obtained by prior machines.

5 A further object of this invention is to simplify the construction of known machines for testing yarn strength.

A still further object of this invention is to 10 make the working of such machines fully automatic.

With these and further objects in view, the invention consists of certain new constructions, arrangements and combinations of parts. 15 Among them, the most important is the provision of a distributor supplying threads from a plurality of bobbins and operated in such manner that said threads from the various bobbins are automatically brought one after another 20 within the range of the mechanism introducing them into the tensile straining device.

The change of the bobbins takes place as soon as a determined number of tests have been carried out on the thread of one bobbin.

25 The drawings show by way of example a tester embodying the features according to this invention.

Figures 1 and 2 show in continuation of each other a side view of the apparatus.

30 Figure 3 is a plan view of Figure 2 and part of Figure 1.

Figure 4 is a front view of a portion of the recording mechanism drive.

Figure 5 is a front view of a clamp of the 35 tensile straining device.

Figure 6 is a front view of the distributor or thread changing device.

Figure 7 is the wiring diagram, and

Figure 8 is a partial plan view which illustrates 40 the feeding of the threads from the bobbins to the distributor.

The apparatus comprises, in combination, the thread distributor, a tensile straining device, the feed device introducing the thread between the 45 two clamps of the tensile straining device, the pulling device connected with one of the two clamps and the recording mechanism connected with the other clamp. The apparatus is further provided with hand-operated switches for actuation by the operator.

50 The thread F to be tested is stretched between two clamps shown diagrammatically in Figures 1 to 3 where they are designated by 1 and 1a, and the construction of the same will be described with reference to Figure 5 where it is

shown in greater detail. The clamp 1 (Figures 1 and 3) is carried by one end of the rod 2 sliding horizontally between guides 2a and 2b and of which the other end is provided with a chain 3 attached to the pulley sector 4 keyed on the shaft 5, to which is also keyed the pendulum 6, said pendulum being lifted in clockwise direction when the clamp 1 is drawn by the thread F towards the right. The pendulum has rigidly attached thereto the arm 7 carrying on each side 10 by means of a cross member 8 the pawls 9 and 10 engaging the sawteeth of the sector 12 and wheel 16, respectively.

The toothed sector 13 is connected through the shaft 5 with the sector 12 and meshes with 15 the sector 14 on the arm 15 which latter is journaled on the frame of the machine and actuates through the link E₁ a recording needle T₁ guided between rails G₁. The wheel 16 drives through a reducing gear constituted by the toothed wheels 20 17 a second sector equal to and co-axial with the sector 14, said second sector actuating through an arm equal to the arm 15 (said sector and arm are not visible in the drawings, being covered by sector 14 and arm 15) and the link 25 E₂ a further needle T₂, guided between rails G₂. The ratio of the reducing gear is $n \times m$ (m= 30 number of bobbins, n=number of tests on each bobbin), so that the stroke of the needle T₂ for a given rotation of the shaft 5 is $n \times m$ times 35 smaller than that of the needle T₁. A chart of some kind is moved under the needles. This mechanism is not illustrated because it may be a common one in the pertinent art. By way of example, supposing m to be equal to seven and n 35 to be equal to ten, the needle T₂ performs a movement which is one-seventieth of the movement of the needle T₁. The toothed sector 14 is under the action of the weight 18 articulated to an arm thereof (Figure 1). Therefore, when 40 the pawl is disengaged from the sector 14, the needle T₁ turns to zero. The toothed wheel 16, however, under the action of a friction brake 19 actuated by the spring 19a or by one of the toothed wheels 17 (Figure 4) tends together 45 with its respective needle T₂ to remain in the position to which it has been brought. When the thread F draws the clamp 1 towards the right, due to the operative connections just described (rod 2, chain 3, sector 4, shaft 5, arm 7), 50 the pawls 9 and 10 ride on the sets of sawteeth of the sector 12 and wheel 16, respectively. When the thread breaks the arm F with the pawls 9, 10 returns under the action of the pendulum 6 and said pawls engage the teeth of 55

sector 12 and wheel 16, respectively, rotating them to an extent proportional to the height by which the pendulum 6 has been lifted, namely, to the load having broken the thread. At the 5 end of the return stroke the pawl 9 is disengaged from the sector 12 by the abutment 11, the sector 12 is restored to zero by the action of the weight 18, and the wheel 16 remains in the position to which it has been brought by the pawl 10. 10 Consequently, the next record by the needle T₂ shall start from the apex of the line of the first test, and so on; at the end of the $n \times m$ (seventy) tests the apex of the diagram described by this 15 needle T₂ gives the mean value of the measurements on the same scale as the first needle T₁, average measurement having been made on a seventy times smaller scale.

The second needle T₂ is automatically restored to zero at the end of the $n \times m$ (seventy) tests. 20 For this purpose the brake 19 is provided with an arm 20 releasing the wheel against the action of the spring 19a, whereby the needle T₂ is restored to zero by virtue of the weight of its supporting arm. Arm 20 is actuated by an electro- 25 magnet R, the operation of which shall be described hereinafter. In other words, the needle T₁ marks as many lines as there have been individual tests made. The length of each line corresponds to the breaking load of its respective 30 individual test. This set of lines permits reading of maximum and minimum values. The needle T₂ marks one line only, which is of the same order of length as the lines marked by T₁ and indicates the average breaking load of all 35 tests carried out. The needle T₃ marks, as will be described hereinafter, as many lines as there have been individual tests made, and the length of said lines indicates elongation of the threads in the individual tests.

40 The other clamp 1a of the tensile straining device is carried by the horizontally movable link 21 of the articulated parallelogram formed by the links 21, 22, 24 and member 23 (Figures 2 and 3), the member 23 being fixed to the base plate K of the apparatus. To the shaft 25 is keyed 45 besides the link 24 the long arm 26 whose toothed segment 27 meshes with the pinion 28 to which a very slow rotary motion is imparted by the electric motor P on each test by means of a gear drive 29 controlled by the electromagnet N. By 50 lowering the feeler 30 the thread itself operates a mercury switch 31 carried by the link 21 of the parallelogram, as soon as the thread F at the end of the test breaks, whereby the circuit of the electromagnet N is opened and the parallelogram resumes its zero position by virtue of its 55 own weight.

For recording elongation tests a third needle T₃ (Figure 1) is provided which is guided between rails G₃ and operated through the link E₃ by one of the arms of the beam 32, to the other arm whereof the end of the flexible link 33, which may be a steel wire or band, is anchored, said flexible member being wound upon the pulley 34 of the lever 35 and anchored to the pulley 36 keyed on the shaft 5. A second flexible link 37 is anchored at one end to a fixed member 38, and runs over a second pulley 39 on the lever 35 and is attached at its other end to the pulley sector 40 integral with the bell crank lever 41 which is connected by means of the rod 41a with the link 22 of the pulling parallelogram. The flexible links 33 and 37 are stretched by the weight of the pulleys 34 and 39 and lever 35. The proportions 70 of the lever arms and radii of the pulleys 75

36 and 40 are such that when the distance between the clamps 1, 1a remains unvaried, that is to say if the clamp 1a does not move forward by an extent greater than the clamp 1, the beam 32 does not move, while if the clamp 1a advances to a greater extent than the clamp 1, the beam 32 performs an oscillation proportional to the difference between the two displacements, namely to the thread elongation which is thus recorded by the needle T₃. 10

At each test the broken thread is automatically replaced by a fresh thread which is pulled either from the same bobbin or, after n tests (ten in the above mentioned example) on a bobbin, from a further bobbin the thread of 15 which is substituted for the former by the distributor.

The introduction of the thread into the clamps 1 and 1a is effected by a feed mechanism which is visible in Figures 2 and 3. The feed mechanism comprises a double arm 45 slightly exceeding in length the distance between the clamps 1 and 1a and provided at its ends with resilient pliers formed by two curved plates 46 which are slightly compressed by a spring (not shown) and adapted to catch the end of a thread when it comes within their circular path. The arm 45 is driven in clockwise direction by the electric motor P by means of the toothed wheel 42 through a clutch 43 operated by the electromagnet M, so that the arm 45 performs half a turn when the pendulum 6 is returned to zero. The wheel 42 is keyed on the shaft 44 at equal distances from the two clamps. To the same shaft 44 is further keyed the hub of said double arm 45. A cam disc 47 is keyed on the same shaft 44 and is formed with a circular groove 47', having two re-entering portions in the form of large V's at opposed points on the diameter perpendicular to the arm 45 only one of these V's being visible in Figure 2. A roller 48 runs in this groove and to the pivot thereof are articulated the ends of the two beams 49 rockably mounted on the pivots 49a of a vertical fixed plate L, the pivots 49a being adjustable in height. The free ends of the beams 49 by means of wedges 49b carried thereby open and hold open the clamps 1 and 1a. The clamps are opened as soon as one of the pliers 46 has caught the end of the thread due to the dropping of the wedges 49b when the roller 48 leaves the notch in the groove 47'. When the roller 48 re-enters a notch in the groove 47', the wedges 49b are raised and the clamps 1 and 1a closed, the latter shortly after the former. The feeler 30 being lowered, pulling of the thread starts by the action of the articulated parallelogram, while the feed mechanism remains inoperative and in a well-defined position. The clamps 1 and 1a comprise each (Figure 5) a jaw 50 fixed on the link 21 with a thread-guide 50a, and a jaw 51 articulated to the former and provided with a spring 52 which keeps it close to the jaw 50. A small arm 53 having a roller 53' is secured to the jaw 50 which carries the pin 50b for the bell crank lever 54 of which one arm carries the roller 54' opposing the roller 53', and the other arm whereof is formed with a tooth 55 which by riding on an inclined surface 51a on the jaw 51 may push this latter away from the 70 jaw 50 against the spring action. The tooth 55 is caused to ride on the surface 51 by drawing the two rollers 53' and 54' away from each other by the wedges 49b of the beams 49 during rotation of the arm 45. 75

The distributor (Figures 1, 6, and 8) comprises a sector 56 rotatable about a pivot 56' parallel to the thread F and situated to the left of the pliers 46 of the feed mechanism. The sector 56 is formed at its lower part with a set of saw-teeth 57 and at its periphery on a segment of wood 58 an eyelet 59 and a small arm 60 are provided for each bobbin, the small arm 60 being equipped with a spring 61 forming with the arm resilient pliers. In Figure 6, the five first pliers 60, 61, etc., are omitted for the sake of clarity. The end F' of the thread F on each bobbin runs through the eyelet 59 and is placed between the pliers 60, 61 before a series of tests (Figure 8).

The circular path of the pliers 46 of the feed mechanism intersects the line of the thread end F'. On raising the left hand pliers 46, they will engage the end F' of the thread and carry same first to the left of and then over the clamp in a semi-circular movement, thereby drawing the thread F from the bobbin. At a determined position of the pliers during this movement the thread F is inserted from above into the clamp 1, whereupon the latter closes under the action of the above described mechanism. Shortly thereafter, the thread from above also arrives into the clamp 1a, whereupon the latter closes. When the pliers 46 have reached the end of their semi-circular displacement, the thread that had first been held by clamp 1 and then by clamp 1a, has been fully drawn out from the pliers, this being made possible by the particular construction of the pliers 46 from parts which are lightly pressed against each other by springs. In preparing for the next test the other pliers 46 now turned towards the distributor meet the length F'' of the same thread no longer retained by the pliers 60—61 situated between the clamp 1 and eyelet 59, and so on for an n (ten) number of times preset. A suitable mechanism hereinafter described closes after these tests on a bobbin the circuit of the electromagnet S. The armature of said electromagnet S is connected with a pawl 62 acting on the set of teeth 57. Therefore, every time the electromagnet S is actuated, i. e., after n tests made on the same thread, the sector 56 is rotated through said angle thereby bringing the end F' of the thread on the next bobbin into the path of the pliers 46. Figure 6 shows in dot and dash lines the position of the sector 56 before the tests and in full lines the position after 7 (=m) forward movements. n (=10) tests on the same thread have been carried out between two successive forward movements.

In Figure 8 the position of the sector 56 drawn in full lines is the position before the tests and the one in dot and dash lines is the position after $m \times n$ tests have been carried out. The bobbins are fitted on a corresponding number of spindles 10 carried by the bedplate K of the apparatus (Figures 4 and 8). As the clamp 1a opens the broken tested threads will automatically fall off.

Actuation of the electromagnet S is effected by means of a wheel Z (see diagram in Figure 7) which performs a fraction

$$\frac{1}{m \times n}$$

(a seventieth) of a turn at each test and is driven by means of a pawl and ratchet gear by the rod 41a, that is to say by the pulling device. The wheel Z is provided on its periphery with as many

notches, teeth or the like as there are m (seven) spindles under test, by means of which it closes for an instant the said circuit of the electromagnet S every n th (tenth) displacement.

The various elements of the apparatus are actuated one after another automatically in the desired order by virtue of the interlocking of electrical circuits according to the diagram in Figure 7. On a main circuit connected to the supply line are shunted the circuits for the electric motor and electromagnets operating the various members, in which mercury switches are connected. The circuit A of the motor P is provided with a hand-operated switch 71 which shall be actuated by the operator. The circuit B of the electromagnet N of the gear drive 29 for the pulling device includes the mercury switch 31 connected in series with the electromagnet N and actuated by the feeler 30. In the circuit C of the electromagnet M for the clutch 43 for the feed mechanisms there is a mercury switch 63 which is connected in series closed by the pendulum 6 when the latter is in its zero position, and the pair of delay-action switches 64, 65 in parallel with each other and acted upon alternately by either end of the arm 45. Consequently, the clutch 43 for the feed mechanism is not coupled unless the pendulum has been fully restored to zero and one of the switches 64 and 65 has at the same time closed. Upon breaking the thread, the pendulum sinks and closes the switch 63. The switch 64 being closed, the clutch is coupled and the double arm 45 is set in rotation; after half a turn, one end of said arm opens the switch 64 which closed the circuit, while the feeler closes the switch 31. The arm is arrested and the pulling device is set in operation, the pendulum 6 rises till completion of the test and the process is repeated alternately by the action of the other end of the arm 45. A mercury switch 66 is placed in the circuit D of the electromagnet S of the distributor and is closed for an instant by the actuating wheel Z every n th (tenth) test; a further switch 67 is available to the operator who, by opening this switch, is able to discontinue the operation of the distributor and effect any desired number of tests on one and the same spindle. When the $m \times n$ tests are completed, the same wheel Z closes by means of a tooth y the switch 68 of the circuit E of the electromagnet R which performs the function of releasing the brake 18 by means of the arm 29 (Figures 1 and 4), thus restoring the needle recording T₂ to zero. The switch 68 is connected in series with a further mercury switch 69. For this reason the closure of switch 68 is not yet sufficient for the energization of the electromagnet R and release of brake 18, which may take place only after switch 69 has also been closed. This switch is controlled by the pendulum 6 in such manner that it closes when the pendulum has returned to its rest position. As explained above, the pendulum resumes its initial position only after a test registration has been fully completed. Consequently, the brake is released and the needle T₂ resumes its initial position only when the last $m \times n$ test has been fully recorded.

I wish it to be understood that I do not desire to be limited to the exact details of construction shown and described, for obvious modifications will occur to a person skilled in the art.

What I claim is:

1. A machine of the type described for testing threads from a plurality of bobbins, comprising

ing in combination a tensile straining device, a mechanism for introducing a specimen into said tensile straining device, a distributor carrying separately threads from the plurality of bobbins, members adapted to advance the distributor to such an extent that the threads from the individual bobbins come successively within range of said introducing mechanism and automatic means adapted to actuate said members for advancing the distributor after a determined number of tests.

2. A machine of the type described for testing threads from a plurality of bobbins, comprising in combination a tensile straining device, a mechanism for introducing a specimen into said tensile straining device, clamps in said mechanism, for the specimens, a distributor, nippers and an eyelet on said distributor for the thread from each bobbin, said nippers and eyelet being arranged on either side, respectively, of the path of the clamps of said introducing mechanism, members adapted to advance the distributor by such extent that the connecting threads between the paired eyelets and nippers come successively within range of said clamps of the introducing mechanism and automatic means adapted to actuate said advancing members after a predetermined number of tests.

3. A machine of the type described for testing threads from a plurality of bobbins, comprising in combination a tensile straining device, clamps on said tensile straining device for the specimens, a member adapted to introduce the thread into said clamps and free to rotate, means adapted to impart to said member at each test a rotation in a constant direction, pliers on said member for holding said threads during their introduction, a distributor carrying separately thread lengths from the plurality of bobbins, members adapted to advance the distributor by such extent that the lengths of the said various threads come successively within range of said pliers and automatic means adapted to actuate said advancing members after a predetermined number of tests.

45 4. In a machine for testing yarn specimens of

the type described, the combination of a pair of clamps for holding the specimens, a parallelogram one side whereof carries one of said clamps a feeler arranged between said clamps and operated by the specimen, an electric switch actuated by said feeler, on a mechanism for displacing the parallelogram, a clutch in said mechanism and an electric device for actuating said clutch in the supply circuit whereof said switch is placed in such manner as to disengage the clutch for stopping the displacement of said parallelogram when the specimen breaks and to engage the clutch for displacing the parallelogram when a sound specimen is stretched between the clamps.

5. In a machine for testing yarn specimens of the type described, the combination of a pair of clamps for holding the specimens, a pulling mechanism connected with one of the clamps, a recording mechanism and, in said recording mechanism, a transmission member connected with the other clamp, two pawl and ratchet gears the driving members whereof are actuated by said transmission member, two needles for recording the individual breaking loads and the average breaking load, respectively, two drives with different transmission ratios between said needles and the two driven members of the pawl and ratchet gears, means for restoring to zero one of said driven members after each test and a brake acting on the driven member of the other gear for holding this member in the position reached after each test.

6. In a machine for testing yarn specimens of the type described, the combination of a pair of clamps for holding the specimens and a pulling mechanism connected with one of the clamps, a recording mechanism and in said recording mechanism, a needle for recording elongation of the specimens, a flexible link between the first clamp and said needle, a second flexible link connected with the pulling mechanism, two rollers adapted to stretch said flexible links and a common support for said two rollers.

ARRIGO PAGNACCO. 45
